DRAFT RIGGING

Byers W. Kadel, Baltimore, Md., assignor, by
mesne assignments, to The Symington Com-
pany, New York, N. Y., a Corporation of Mary-
land

Application October 30, 1924. Serial No. 746,770

2 Claims. (Cl. 213—30)

The invention relates to draft rigging and more particularly to a shock absorbing unit adapted for use as the cushioning unit of railway draft rigging.

5 The principal object of the invention, generally considered, is to provide a cushioning unit of high capacity and low recoil which may be advantageously substituted for the friction cushioning elements now in general use and in which 10 the primary cushioning unit comprises a nest of spring plates.

A further object of the invention is to provide a shock absorbing unit having a multi-part casing, the parts of the casing being interlocked 15 so as to prevent separation thereof and at the same time permit relative longitudinal movement between the same and to house within said casing cushioning elements arranged to offer a high resistance to closing loads without excessive recoil shocks.

Another object of the invention is to provide a plurality of interconnected casings so arranged that loads in excess of the cushioning elements housed within the casings are transmitted from 25 one casing to the other and from thence to the car sills without detriment to the casings, cushioning elements, or associated parts.

Still another object of the invention is to provide a simple, compact and reliable cushioning unit having means whereby parts thereof are interconnected so as to prevent not only the disassembly but the wrong assembly of the mechanism.

To these and other ends the invention comprises the various elements and combinations of elements as hereinafter set forth.

In the drawings:

Figure 1 is a view partially in plan and partially in section of a railway draft rigging and 40 associated attachments showing the invention.

Figure 2 is a longitudinal vertical section of the cushioning unit of my invention.

Figure 3 is a view partially in side elevation and partially in vertical section of the construction shown in Figure 2.

Figure 4 is a longitudinal sectional view taken on the line 4—4 of Figure 7, the direction of view being indicated by the arrows adjacent the ends of the section line.

50 Figure 5 is a longitudinal sectional view taken on the line 5—5 of Figure 7, the direction of view being indicated by the arrows adjacent the ends of the section line.

Figure 6 is a front elevation of the cushioning unit forming the subject-matter of my invention.

55 Figure 7 is a cross-section on the line 7—7 of Figure 2, the spring being omitted for the sake of clearness.

Figure 8 is an elevation of the rear casing with 60 the cushioning spring omitted.

Figure 9 is a fragmentary sectional view similar to the rear section of Figure 4, showing, however, the position the plates assume under compression.

Throughout the drawings and specification 65 like parts are designated by like reference characters.

The numeral 1 designates the draft or center sills of a car to which I have, for convenience, shown applied the well known two-key Farlow 70 attachments. The said attachments comprise a pair of slotted cheek plates 2—2 having front slots 3 and rear slots 4 therein, the said slots being adapted, respectively, to accommodate the coupler key 5 and the front follower key 6. 75 Between the sills there is located the usual horizontally disposed yoke 7 which is likewise provided with slots 8 and 9 for the reception, respectively, of the said keys. 10 is the front follower block through which the key 6 passes 80 and by which, through the instrumentality of said key, the shocks and strains, due to draft on the coupler 11, are transmitted to the cheek plates 2 and from the latter to the sills 1. At its inner end the yoke 7 bears against a stop 85 member 12 which bridges the sills and by which buffing shocks, due to the inward movement of the coupler 11, are transmitted to the car sills. 13 is the rear follower which is preferably provided with ears 14 which overlie the upper faces 90 of the adjacent portions of the yoke 7 and maintain said follower in assembled position, and interposed between the followers 10 and 13 is the cushioning unit 15 which forms the subject-matter of my invention. It will be understood 95 that the cushioning unit hereinafter described is adapted for use with either vertical or horizontal yokes both of which are equally well known, and that the illustration of the device in connection with the Farlow two-key is not a limitation to 100 its use in this connection.

The cushioning unit 15 comprises a pair of casings 16 and 17, the casing 16 being preferably rectangular in outline and being provided with a rectangular opening 18 for the reception of the plate springs 19 hereinafter to be more fully described. At its forward end the casing 16 is provided with a plurality of pairs of recesses 20 which are preferably symmetrically arranged with reference to the longitudinal and horizontal axes of the casing. The said recesses are adapted to receive correspondingly shaped lugs 21 formed on appropriate parts of the cylindrical outer casing 17. The last named casing is preferably formed as a hollow shell having a closed bottom 22 and projecting outwardly therefrom is a head or bearing member 23. Said head is substantially rectangular in outline and is adapted to fit within the opening 18 of the casing 16. The opposite vertical side edges of said head 23 110 115 120

are each struck on arcs of equal radii, the centers of curvature of said arcs being spaced apart so that the curvature of one edge is the reverse of the curvature of the opposite edge, 5 as clearly shown in Figure 3. The two edges are connected by a convex portion, the axis of which is disposed diagonally of the two vertical side edges. Owing to the reverse curvature of the side edges of the head 23 and owing to the fact 10 that the head 23 is of greater extent than the neck portion 24 which connects the same to the bottom wall 22, there are provided, at diametrically opposite corners of the head, shoulders 25 and 26, the shoulders 25 being in one plane and 15 the shoulders 26 being in another parallel plane. This construction provides means for interlocking 20 by connecting the casings 16 and 17 and at the same time provides means for preventing the wrongful assembly of said parts. At one pair of diagonally opposite corners I provide 25 interlocking elements such as a pair of rods or rivets 27, and at the other diagonally opposite corners I provide another pair of rods or rivets 28, the interlocking elements such as rods 27 being placed closer to the open end of the casing 16 than are the rods 28 and since the head 23 of the casing 17, owing to the lugs 21, can only 30 be assembled with the casing 16 in certain positions and since it is only possible to insert the rods 27 when the shoulders 25 are in the proper position, and only possible to insert the rods 28 when the shoulders 26 are in proper position, it necessarily follows that there is only one way to 35 assemble the casings 16 and 17. After the casings have been assembled the rods 27 and 28 may have their ends riveted over, as at 29, to prevent the separation of the casings during shipment.

The casing 17 is provided in the bottom wall 22 with a screw-threaded opening 30 for the reception of the bolt 31 which is provided at its opposite end with a head 32 seated and housed in a thimble or inwardly embossed spring-centering portion 33 of the follower 34. Interposed between the inner face of the follower 34 and the bottom wall 22 of the casing 17, is a friction spring mechanism 35 and enclosed within the friction spring mechanism is a coil spring 35^a. Both the friction and coil springs preferably bear at opposite ends against the follower 34 and wall 50 22, respectively, and it will be obvious that any desired preliminary compression may be maintained by the adjustment of the length of the bolt 31, that is the free extension of said bolt from the wall 22.

55 The casing 16 is also provided with a closed end 36. The said closed end 36 is a counter-part of the projecting head 23 except that it is concave rather than convex. At opposite diagonal corners, corresponding to the location of the shoulders 25 on the head 23, there is suitably mounted in recesses 37 in the face or end wall 36 rocker members 38, said rocker members being adapted to engage the diagonal corners of the rear rectangular plate of the plate springs 60 19. The foremost plate of the plate springs 19 is adapted to engage the projecting face of the head 23.

The casing 16 may be provided with a rearwardly extending portion 39 which may be cored, 70 as shown at 40, for the sake of lightness, the projection 39, when the device is in service, being adapted to engage the follower 13 of the draft rigging.

75 It will be observed that the plate spring member 19 comprises a plurality of flat spring plates

in face to face contact and it will also be noted that I have shown the springs of unequal thickness. The greater number of plates employed causes a corresponding increase in the frictional resistance generated by the sliding contact of one plate on the other and in this manner the recoil shocks generated by the spring plates 19, returning from the position shown in Figure 9 to the position shown in Figure 4, is to a large extent dissipated by the frictional resistance.

To obviate wear on the corners opposite to the corners in which the rocker members 38 are located, I preferably provide the casing 16 with angle hardened wear plates 41 which are conveniently attached to the casing by means of the bolts 28 through the corresponding corners.

The operation of the device is believed to be obvious from the foregoing description but it might be pointed out that on the initial compression of the cushioning device either by draft or buffing movements of the coupler, there is first interposed a combined frictional and spring resistance of the friction spring 35 and the coil spring 35^a and that this resistance increases progressively until such time as the follower 10 of the draft gear here illustrated contacts the forward end of the casing 17. This contact of course limits the compression and movement of the springs 35 and 35^a and upon a further movement of the coupler in the same direction

105 the casing 17 is caused to slide relatively to the casing 16, thereby owing to the shape of the faces 23 and 36, causing a flexure of the plate springs 19 along a diagonal line, and owing to the capacity of the nested plate springs, the resistance of the cushioning unit is rapidly increased to a point sufficient to overcome the force moving the coupler. In case that the resistance is insufficient it will be observed that the casing 17, and more particularly the lugs 21, 115 thereof will contact with the rear faces of the recesses 20 and hence any overload in excess of the capacity of the cushioning unit will be transmitted from one casing directly to the other and from the latter casing to the stationary follower. 120

Having now described my invention what I claim is:

1. A cushioning mechanism including a pair of slidably connected casings, plate springs within one of said casings adapted to contact an integral portion of the other, a coil spring mechanism within said other casing, a follower engaging the free end of said coil spring, and interengaging means on said casings for preventing rotation, said means being adapted to transmit from one of said casings to the other forces in excess of the capacity of said plate springs.

125 2. A cushioning mechanism for railway draft rigging comprising a housing substantially rectangular in cross section, resilient means in said housing, a follower positioned in said housing for flexing said resilient means, the surface of the follower toward said resilient means being convexly curved diagonally with respect to the engaged housing and formed with outstanding lugs 135 fitting the corners of the housing whereby adjacent lugs are positioned in different transverse planes and means extending through the corners of the housing at positions corresponding with 140 the lugs on the follower for holding said follower in assembled relation with respect to the housing.
